UNITED STATES PATENT OFFICE.

GEORGE LITTLEFORD, OF FORT THOMAS, KENTUCKY, AND JOHN C. KUYKENDALL, OF CINCINNATI, OHIO; SAID KUYKENDALL ASSIGNOR TO SAID LITTLEFORD.

WOOD-SURFACING MECHANISM.

Application filed July 21, 1920. Serial No. 398,026.

To all whom it may concern:

Be it known that we, GEORGE LITTLEFORD and JOHN C. KUYKENDALL, citizens of the United States, residing, respectively, at Fort 5 Thomas, Campbell County, State of Kentucky, and at Cincinnati, in the county of Hamilton and State of Ohio, have invented certain new and useful Improvements in Wood-Surfacing Mechanism, of which the 10 following is a specification.

Our invention relates to improvements in wood surfacing and jointing mechanism. One of its objects is to provide improved mechanism to accurately surface lumber and 15 other wood work. Another object is to provide improved means to surface opposite sides of wood work so that the opposite faces are relatively parallel and true. Another object is to provide improved feeding 20 means to hold and feed the stock relative to the cutter mechanism and insure passage of the stock along a prescribed path. Another object is to provide an improved and adjustable feed table. Another object is to 25 provide improved adjustable chain feed mechanism. Another object is to provide improved means to surface and dress stock to a uniform thickness. Our invention also comprises certain details of form, combination, and arrangement, all of which will be 30 fully set forth in the description of the accompanying drawings, in which:

Fig. 1 is a side elevation of our mechanism.

Fig. 2 is a perspective view of the feed carriage detached.

Fig. 3 is a front end view of the mechanism of Fig. 1.

Fig. 4 is a sectional detail of the feed 40 chain and its supporting and guiding means.

Fig. 5 is a side elevation of one of the gravity feed pawls.

Fig. 6 is a plan of the forward feed table section detached.

Fig. 7 is an enlarged sectional detail on line 7—7 of Fig. 6.

The accompanying drawings illustrate the preferred embodiment of our invention, in which 14 represents the main frame to the 50 machine, on which is adjustably supported a saddle 15 on which is journaled a shaft 16 provided with a rotary cutter head 17. In front of the cutter head and rigidly attached to the main frame are a series of inclined 55 blocks or ways 18 on which are movably

mounted inclined blocks 19, which are rigidly attached to the under face of the forward table section 20. The blocks 18 and 19 are preferably arranged with laterally engaging faces at 21, Fig. 3, to hold the table in place 60 against lateral displacement and to cause the table 20 to travel only in one direction to and from the cutter head. A link 22 is pivotally connected at one end to the table 20, and at the opposite end to a weighted lever 65 23, which is pivotally supported at 24 relative to the main frame and at its free end is provided with a weight 25 having a limited movement tending to force the table 20 toward the cutter head, which also due to the 70 inclined faces by which the table 20 is mounted upon the main frame, tends to elevate the table 20 as it moves toward the cutter head, and to lower the table 20 as it moves away from the cutter 75 head. In rear of the cutter head is a table 26 which is mounted by means of inclined blocks 27 carried thereby, upon inclined blocks 28, which are rigidly attached to the main frame. The table 26 is laterally 80 guided so as to be adjustable only to and from the cutter head, and to be elevated when moved in one direction, and to be lowered when moved in the opposite direction. It is designed that the table 26 shall 85 be adjusted from time to time as required so that the upper face of the table shall be horizontally in line with the upper limit reached by the cutting edge of the cutter head. Means is provided, as for instance 90 the projections 29 and 30, and clamping bolts 31, to rigidly clamp the table 26 to its adjusted position relative to the main frame.

Projecting above the main frame and supported thereby are a plurality of columns 95 32 provided with vertical ways 33 which are engaged by ways or guides 34 carried by an open cage 35. Feed screws 36 mounted upon the columns and provided with miter gears 37 engage nuts 36' and serve to raise and 100 lower the cage 35 along the ways 33 of the columns. Actuating shafts 38, 39, and 40 are provided with miter gears 41 to mesh with the miter gears 37 of the several feed screws 36, so that all of said feed screws 105 may be actuated by hand in unison through a hand wheel 42 on the shaft 38 to raise or lower the cage 35.

The cage 35 is preferably a rigid structure, as for instance of cast iron, provided 110

with journals for the shafts 43 and 44 on which shafts are mounted sprocket wheels 45 and 46. A feed belt or chain 47 is movably supported upon the sprocket wheels 45 and 46 and the links of said chain are provided with channels or guide-ways 48 at opposite edges to engage with the guides or ways 49 seated in channels 50 cut in the inner faces of the cage 35, and adjustable 5 therein by means of set-screws 51 and 52 so as to take up substantially all lost motion between the chain links and the cage 35 where the chain links serve as a guide and support for the stock to be surfaced. In 10 order to take up the lost motion between the chain links and the guides 49, one contact face of each is beveled as shown at 53 Fig. 4. The respective chain links are preferably provided with one or more pawls or dogs 15 54, preferably gravity actuated and seated in recesses in the links and provided with teeth 55 to engage the face of the stock and prevent the stock slipping backwardly under the action of the cutter head, relative to the 20 chain links.

The end of the forward table 20 nearest to the cutter head is recessed to receive a plurality of pivotally attached levers 57, which are yieldingly held in substantially the position shown in Fig. 6 by means of the springs 58. The sharp free ends of levers 57 are designed to bear against the under side of the stock yieldingly, and in the event that the stock, or any portion of the stock being 25 fed through the machine should be of less thickness originally than the minimum space between the table 20 and the chain links, to automatically engage and dog the stock from the under side, so that the stock cannot be 30 fed backwardly under the action of the cutter head. Said levers 57 also tend to force stock passing between the table 20 and the chain upwardly against the chain so that the stock is firmly in contact with the chain 35 and so that the dogs 54 of the chain links are in engagement with the upper face of the stock. The table 20 is also provided with a series of recesses in which are pivotally mounted levers 60 each preferably provided 40 at its free end with a roller 61, and acted upon by means of a spring 62 to yieldingly force the stock upwardly against the under face of the chain links and into position for the stock to be engaged by the dogs 54 carried by the chain links.

In practice the movement of the weight 25 is limited by the weight striking the floor, or by other means so that the upper limit of movement of table 20 is insufficient for said 50 table to contact with the undersurface of the chain links or the dogs 54. A counter shaft 64 by means of a pulley 65 and belt 66 serves to drive the cutter head shaft 16 through the pulley 67 at a relatively high rate of 55 speed. A pulley 68 of smaller diameter on

the counter shaft 64 by means of a belt 69 drives a pulley 70 and shaft 71 on which is a pulley 72, which by means of a belt or sprocket chain 73 and pulley 74 on the shaft 43, serves to drive the chain 47 and its 70 sprocket wheels at a relatively slow rate of speed.

In operation, the hand wheel 42 is employed to vertically adjust the cage 35 and the feed chain carried thereby until the under face of the chain is a sufficient distance above the upper limit of the cutter head for the passage of the particular type of stock it is desired to surface. The table 26 is adjusted vertically so that the space between 75 the upper face of table 26 and the under face of the feed chain is the same as between the under face of the feed chain and the upper limit of the cutter head. The stock to be surfaced is then fed in between the table 80 20 and the under face of the feed chain by hand or automatic feed until the feed chain secures sufficient grip to continue the feed automatically. The table 20 and the yieldingly supported levers carried thereby serve 85 to hold the upper face of the stock firmly against the under face of the feed chain irrespective of whether the thickness of the stock at one end or at both ends is greater than the distance between the cutter head 90 and the under face of the feed chain. Where the stock is of greater thickness, the cutter head engages the stock and removes the surplus, thereby surfacing the under face of the stock in whole or in part, until the stock 100 will pass between the feed chain and the table 26. Where the stock through a portion of its length is of less thickness than the space between the feed chain and the cutter head, the table 20 and its adjunct levers 105 serve to hold that portion of the stock in contact with the feed chain and out of contact with the cutter head, and at the same time prevents liability of the stock to feed 110 backwardly. After a sufficient amount of stock has been fed through the machine and surfaced on one side, the feed chain is readjusted to a position closer to the cutter head, and the stock fed through again after reversing it to present the unsurfaced face 115 to the cutter head. Any pieces of stock which are not entirely surfaced upon both sides may be discarded or used to the extent that they have been surfaced on both sides. Since in practice it is liable to happen that 120 the rear end of one stock piece is relatively of less thickness than the majority of the stock, while the forward end of the next stock section may be of greater thickness than the majority of the stock, thereby forcing the table 20 downwardly by the introduction of the second stock member before the rear end of the first stock section has cleared the cutter head, it is important for the levers 57 and 60 to be in position to yield. 130

ingly engage the rear end of the stock section of less thickness until it shall have practically all passed the cutter head, and to prevent it from dropping down upon the cutter head or feeding backwardly by reason of its not having a firm engagement with the feed chain.

The mechanism herein illustrated and described is capable of considerable modification without departing from the principle 10 of our invention.

What we claim is:

1. In combination with a rotary cutter to surface one face of the stock, a first carriage 15 movable to and from said cutter and provided with a plane face between which and said cutter the stock is fed, a stock supporting member having a plane face parallel to the plane face of said carriage on the same 20 side of the stock with and in rear of said cutter and held in fixed relation to the cutter, and a carriage on the same side of the stock with said cutter and in advance of said cutter having a plane face continuously held 25 substantially parallel to the plane face of said first carriage and yieldingly adjustable to and from the plane face of said first carriage.

2. In a wood surfacing machine, a feeding 30 belt at one face of the stock to be surfaced traveling along a stationary guide to retain the feeding face of said belt in substantially one plane, a rotary cutter to surface the side of the stock opposite said feeding belt, a 35 table section in rear of said cutter having a fixed position with reference to said cutter, and having a plane face opposite and continuously substantially parallel with the plane face of said feed belt, and a table section 40 in advance of said cutter having a plane face held continuously substantially parallel with and opposite to the plane face of said feed belt and yieldingly adjustable to and from the plane face of said feed belt to 45 yieldingly hold the stock in contact with the plane face of said belt.

3. In combination with a rotary cutter to surface one face of the stock, a table section in rear of said cutter having a plane face adjustable 50 into alignment with the cutting edge of said cutter and adapted to be locked in fixed relation to the cutter, a table section in advance of the cutter having a plane face adjustable yieldingly transversely to its 55 plane face to a plurality of plane parallel positions, and a feed-belt having its feeding face opposite to said cutter and the plane faces of said table sections in a plane parallel to the plane faces of said table sections to 60 feed the stock forward across the cutter between the cutter and feed belt.

4. In combination with a rotary cutter to surface one face of the stock, a first stock supporting member provided with a plane 65 face between which and said cutter the stock

is fed, a second stock supporting member having a plane face parallel to the plane face of said first stock supporting member on the same side of the stock with and in rear of said cutter and held in fixed relation 70 to the cutter, and a third stock supporting member on the same side of the stock with said cutter and in advance of the cutter having a plane face continuously held substantially parallel to the plane face of said first stock supporting member and yieldingly adjustable to and from the plane face of said first stock supporting member.

5. In combination with a rotary cutter to surface one face of the stock, a carriage movable to and from said cutter to predetermine the space available for the passage of the stock, a feed belt carried by said carriage and having a plane feeding face opposite said cutter, a stock supporting member in 80 rear of the cutter having a plane face adjustable into alignment with the cutter and substantially parallel with the plane face of said feeding belt and adapted to receive the faced stock between said stock supporting member 85 and the plane feeding face of the feed belt to guide the stock away from the cutter, and a second yieldingly adjustable stock supporting member forward of the cutter having a plane face opposite and continuously 90 substantially parallel to the plane face of said feed belt adapted to automatically force the stock forward of said cutter away from the cutter and against the plane face of said feed belt.

6. In combination with a rotary cutter to surface one face of the stock, a first stock supporting member opposite to and extending both forwardly of and rearwardly of said rotary cutter to support and feed the 105 stock and provided with a plane face between which and said cutter the stock is fed, a second stock supporting member having a plane face parallel to the plane face of said first stock supporting member on the same 110 side of the stock with and in rear of said cutter and held in fixed relation to the cutter, and a plurality of resiliently mounted stock supporting members on the same side of the stock with said cutter and in advance of the 115 cutter to independently bear upon the face of the stock in advance of the cutter to yieldingly hold the stock members in advance of said cutter in contact with the plane face of said first stock supporting member.

7. In combination with a rotary cutter to surface one face of the stock, a carriage movable to and from said cutter to predetermine the space available for the passage of the stock, a stock feeding member carried by 125 said carriage, a table section in rear of the cutter adjustable into alignment with the cutter and adapted to receive and pass the stock between said table section and carriage, and a plurality of members forward of 130

the cutter to independently yieldingly press different stock sections away from the cutter and against said carriage.

8. In combination with a rotary cutter to surface one face of the stock, a carriage movable to and from said cutter to predetermine the space available for the passage of the stock, a stock feeding member carried by said carriage, a table section in rear of said cutter adjustable into alignment with the cutter and adapted to receive and pass the stock between said table section and carriage, and a table section forward of the

cutter adjustable and yieldingly energized to press the stock away from said cutter and toward said carriage, said forward table section being provided with a plurality of independently movable and yieldingly energized members also tending to press the stock away from said cutter and toward said carriage.

In testimony whereof we have affixed our signatures.

GEORGE LITTLEFORD.
JOHN C. KUYKENDALL.
